UNITED STATES PATENT OFFICE

149,181

DESIGN FOR A CREAM SKIMMER

Florence E. Hale, Kit Carson, Colo.

Application February 5, 1946, Serial No. 126,262

Term of patent 3½ years

(Cl. D44—29)

To all whom it may concern:

Be it known that I, Florence E. Hale, a citizen of the United States of America, residing at Kit Carson, in the county of Kit Carson and State of Colorado, have invented a new, original, and ornamental Design for a Cream Skimmer, of which the following is a specification, reference being had to the accompanying drawing, forming part thereof.

In the drawing:

Fig. 1 is a side view of a cream skimmer showing my new design;

Fig. 2 is a front view thereof; and

Fig. 3 is a top view thereof.

I claim:

The ornamental design for a cream skimmer, as shown.

FLORENCE E. HALE.
